FILLING APPARATUS**

Neil S. Stafford, San Jose, Calif., assignor to Food Machinery and Chemical Corporation, San Jose, Calif., a corporation of Delaware

Application September 17, 1954, Serial No. 456,769

6 Claims. (Cl. 251—61)

The present invention relates to valves for fluids or fluidized solids. More particularly, the present invention relates to discharge spouts for vessels containing fluids or fluidized solids.

It is an object of the present invention to provide a valve for fluids or fluidized solids that may selectively be operated to block the flow of fluids or fluidized solids or to permit renewed flow of the fluids or fluidized solids.

Another object is to provide in a conduit, for fluids or fluidized solids, means that normally do not appreciably interfere with the flow of the fluids or fluidized solids therethrough, yet may readily be operated to stop the flow of said substances through the conduit within a minimum of time.

Another object is to provide means operable to block the flow of fluids or fluidized solids through a conduit, spout, or the like, without need to pinch-off or otherwise deform the conduit or spout.

These and other objects of the present invention will be apparent from the following description of the accompanying drawings which illustrate a preferred embodiment thereof and wherein:

Fig. 1 is a fragmentary perspective of a bag filling machine that is provided with a discharge spout embodying the present invention.

Fig. 2 is a fragmentary longitudinal section through a portion of the discharge spout of the machine illustrated in Fig. 1 showing the spout-closing mechanism in inoperative position.

Fig. 3 is an elevation of a portion of the discharge spout, showing the spout-closing mechanism in effective position.

Fig. 4 is a cross section through the spout taken along line 4—4 of Fig. 2 and viewed in the direction of the arrows associated with said line.

Figs. 5 and 6 are combined electric and pneumatic circuit diagrams illustrating different operational positions of the spout-closing mechanism.

Fig. 1 illustrates a discharge spout embodying the invention as applied to an apparatus for filling bags with powdered or granular material, said apparatus being of the type which employs fluidization of the powdered or granular material to facilitate delivery thereof into the bags. Such an apparatus comprises generally a tank 10 which rests upon a suitable pedestal 12. Into said tank the material to be filled into bags is delivered at the upper end thereof and within said tank said material is placed into a condition simulating a fluid by rising currents of air injected into the tank at the lower end thereof from a suitable source of compressed air (not shown) through a conduit 14. The lower section 16 of the front wall 18 of tank 10 is forwardly tilted and carries an inclined spout structure 20. Said spout structure comprises an initial portion in the form of a tube 22 of rigid material, one end of which is suitably attached by a flexible coupling 24 to a collar 26 which is secured to, and surrounds a discharge opening 28 in the front wall 18 of tank 10. The opposite end of the tube 22 may

be rigidly secured to an annular disk 30 which is mounted upon the upper end of a substantially vertical post 32 that forms part of a bag supporting frame 34. Bolted to the frontal face of the annular disk 30 is the flanged end 36 of the terminal portion 38 of the spout structure, which forms the spout proper over which the receiving snout of a bag to be filled is engaged.

Essentially, the bag supporting frame 34 comprises the hereinbefore mentioned post 32 and a saddle 40 which is composed of two transversely spaced parallel bars 42a and 42b that are pivotally supported from the lower end of said post 32. Upon said saddle the bag to be filled is placed during the filling operation while its material-receiving snout is engaged over the spout 38 and is retained on said spout by means of a manually operable clamping mechanism 44 that is arranged above the spout and is supported from the annular disk 30. The bag supporting frame 34 is suspended from one side of a scale which has the form of a U-shaped stirrup 46 that embraces the post 32. The free ends of said stirrup pivotally support the free ends of two L-shaped arms 48a and 48b that are rigidly secured to, and project laterally from, the post 32 of the bag supporting frame 34. At intermediate points the side bars 50a and 50b of stirrup 46 possess outwardly turned ears 52a and 52b, and said ears rest upon knife edges 54 (only one of which is visible in Fig. 1) that are mounted on two parallel girders 56a and 56b which form part of the hereinbefore mentioned pedestal 12 of tank 10. Projecting rearwardly from the crossbar 58 of stirrup 46 is a threaded rod 60 upon which is adjustably engaged a counterweight 62.

Secured to diametrically opposite arcs disposed in axially displaced, yet adjacent, cross-sectional planes of tube 22 are flat inflatable bodies 64 and 66 of a resilient material, such as rubber membrane. Said bodies have somewhat the shape of hollow tongues, and when deflated they are bent in a down stream direction, i. e., toward the discharge end of the spout structure, and lie flat against the inner surface of the tube wall, so as to obstruct the passage formed by tube 22 to a minimum degree, but when inflated they assume a radially extending position within the tube and are of such length as to overlap to some degree. In this matter they block the passage formed by tube 22, as illustrated in Figs. 3 and 4.

Having reference to Fig. 2, the tube 22 is provided with diametrically opposed arcuate slots 68 and 70 disposed in axially displaced, yet adjacent, cross-sectional planes of the tube, and through said slots the inflatable tongues 64 and 66 protrude into the interior of the tube. The open outer ends of the tongues 64 and 66 are provided with outwardly bent flanges 72 and 74, respectively, that lie flat against the outer surface of the tube 22 and which are securely held in position by retaining plates 76 and 78 that are bolted to the tube wall. Said retaining plates close the open outer ends of the hollow bodies 64 and 66 except for centrally located air inlet openings 80 and 82, respectively, which are surrounded by collars 84 and 86, to which may be clamped air supply conduits 88 and 90. The walls 64a and 66a of the tongues 64 and 66, on the downstream side thereof are formed with folds 92 and 94, respectively, in the manner of a bellows which tend to shorten said side walls as compared with the walls 64b and 66b on the upstream side thereof, and as a result the tongues 64 and 66 will bend in a direction toward the discharge end of the spout structure and lie flat against the tube wall when in deflated condition, as illustrated in Fig. 2. In this position they permit fluidized material from tank 10 to pass readily through tube 22 and reach the spout 38 to be delivered into a bag that may be engaged over said spout.

During practical operation of the described bag filling machine the tongues 64 and 66 are held in inflated spout-blocking condition until a bag has been engaged over the spout and the clamp 44 has been brought down upon the bag and the spout to securely hold the former over the latter. For this purpose a strong spring 93 within a pneumatic control valve 95 may be arranged to hold the control body 96 of said valve in a position wherein a source of compressed air (not shown) is applied to both conduits 88 and 90 so that both tongues are fully inflated (Fig. 5). However, closure of the clamping mechanism 44 over the snout of a bag on spout 38 may be arranged to close a switch 98 (Figs. 1, 5 and 6) in the power circuit of a solenoid 100 which operates upon energization to force the control body 96 of the valve against the urgency of spring 93 into a position wherein the source of air pressure is disconnected from the conduits 88 and 90 and both said conduits are connected to the outside atmosphere (Fig. 6). As a result thereof, the two tongues within the tube 22 collapse into the position illustrated in Fig. 2, and material may flow freely from the tank 10 to the spout 38 and into the bag on said spout.

To arrest the flow of material into the bag as soon as the bag reaches a predetermined weight, the power circuit of control solenoid 100 may also include a normally open switch 102 that is mounted upon the girder 56b (Fig. 1) and is ordinarily held in closed position by a lug 104 secured to the connecting bar 58 of stirrup 46. Whenever the stirrup 46 is in the rearwardly tilted position illustrated in Fig. 1, which is indicative of the fact that the weight of the bag on saddle 40 is below the desired value established by adjustment of the counterweight 62, the lug 104 depresses the operating button 106 of the switch 102 and closes said switch. However, as soon as the weight of the bag reaches the upper limit established by the counterweight 62, and the stirrup 46 tilts forwardly, the lug 104 releases the push button 106 and switch 102 opens and interrupts the power circuit of the solenoid 100 (Fig. 5). Upon de-energization of solenoid 100 the spring 93 returns the control body 96 of the valve 95 to the position illustrated in Fig. 5, wherein the connection between conduits 88 and 90 and the outside atmosphere is blocked, and the source of compressed air is applied to said conduits. As a result the tongues 64 and 66 are projected into their radially extending passage-obstructing positions and the flow of the material into the bag ceases.

To avoid interference of the tongues 64 and 66 with each other as they are inflated and move into their radially projecting positions the arrangement should be such that air is first delivered into the tongue 66 on the upstream side and then into the downstream tongue 64. Accordingly, in its travel from tongue deflating to tongue inflating position the control body 96 of the valve 95 is arranged to connect the air supply conduit 90 for the upstream tongue 66 to the source of compressed air slightly ahead of the air supply conduit 88 for the downstream tongue 64, as is apparent from Figs. 5 and 6.

While I have explained my invention with the aid of a particular embodiment thereof, it will be understood that I do not wish to be limited to the specific constructional details shown and described, which may be departed from without departing from the scope and spirit of my invention.

When fluidization of granular or powdered materials is referred to in the above given description and in the following claims, this term is intended to mean not only full fluidization of the said materials, wherein they behave entirely as a liquid, but also all those conditions of lesser aeration which reduce their natural angle of repose and will therefore permit said materials to flow down inclined surfaces that slant at angles less than their natural angle of repose.

I claim:

1. A valve for fluids and fluidized solids comprising a tubular conduit adapted to conduct fluids and fluidized

solids, a pair of inflatable bodies of resilient material disposed within said tubular conduit along diametrically opposite and axially displaced arcs of said tubular conduit corrugations formed in one wall of each of said bodies to prestress said wall and cause said bodies to lie close adjacent the inner wall of said conduit when not inflated, and means operable to introduce fluid into both said bodies to inflate them thereby straightening said corrugations and causing the bodies to swing into a transversely erect conduit-blocking position, said bodies being placed so closely together in a direction axially of said conduit as to come into overlapping contact with each other upon inflation.

2. A valve for fluids and fluidized solids comprising a tubular conduit for the fluids and fluidized solids to pass through in a predetermined direction, a pair of inflatable bodies of a resilient material disposed within said conduit along diametrically opposite arcs in axially displaced yet adjacent cross-sectional planes thereof, said bodies having the form of tongues that lie flat against the inner wall 15 of said conduit in a downstream direction when in deflated condition and which rise in radial direction from said inner wall when in inflated condition, and means operable to successively inflate the upstream body and the downstream body in the order named, said bodies 20 each having a length greater than the radius of said conduit so that their ends overlap when they are in their radially extending, inflated condition.

3. A valve for fluids and fluidized solids comprising a tubular conduit, a pair of inflatable bodies disposed within said conduit along diametrically opposite arcs in axially displaced, yet adjacent, cross-sectional planes thereof, said bodies having the form of tongues with one wall of each tongue being prestressed to cause said tongues to lie flat against the wall of said conduit when 30 in deflated condition and to swing into cooperative contact with each other in transversely erect overlapping positions when inflated to thereby block said conduit, said bodies when in inflated condition each having a length greater than the radius of said conduit so that their ends 35 will assume overlapping positions, and means operable to inflate one of said bodies and subsequently inflate the other of said bodies.

4. A valve for fluids and fluidized solids comprising a tubular conduit for the fluids and fluidized solids to pass through in a predetermined direction, a pair of inflatable bodies of a resilient material disposed within said conduit along opposite arcs in axially displaced yet adjacent cross-sectional planes thereof, said bodies having the form of tongues with one wall of each tongue being prestressed to cause said tongues to lie flat against the inner wall of said conduit in a downstream direction when in deflated condition and to swing into cooperative conduit-blocking contact with each other in transversely erect overlapping positions from said inner wall when in inflated condition, said bodies when in inflated condition each having a length greater than the radius of said conduit so that their ends will assume said overlapping positions, and means operable to inflate the upstream body and the downstream body in succession in the order named.

5. A valve for controlling the flow of fluids or fluidized solids through a tubular conduit comprising a pair of resiliently stressed flexible inflatable bodies fastened to the wall of said conduit, said bodies being in the form 65 of hollow tongues that lie flat against the inner surface of the conduit when in a deflated condition and when inflated swing to a position transverse of the conduit, each tongue having one of its walls prestressed to cause said wall to lie closely adjacent said inner surface when said tongue is deflated, and means for delivering a fluid into 70 said inflatable bodies to inflate them and elongate said prestressed walls relative to their opposed walls to cause said tongues to move into transversely erect overlapping positions within the conduit, said tongues when inflated 75 each having a length greater than the radius of said con-

duit so that their ends will assume said overlapping positions.

6. In a valve for controlling the flow of fluids and fluidized solids through a tubular conduit, a pair of cooperatively associated inflatable valve elements adapted to be disposed within a tubular conduit along axially displaced diametrically opposite arcs of the wall of the conduit, said elements each having one wall prestressed to cause said valve elements to lie against the inner wall of the conduit in the form of generally semi-cylindrical elements when in a deflated condition, and means for inflating said valve elements to elongate said prestressed wall and cause said elements to swing into cooperative conduit sealing overlapping contact with each other in erect positions transversely of the conduit, said elements when in-

5

flated each having a length greater than the radius of said conduit so that their ends will assume said overlapping position.
